United States Patent Office.

JOHN GEORGE KRIECHBAUM, OF YOUNGSTOWN, OHIO.

Letters Patent No. 78,101, dated May 19, 1868.

IMPROVEMENT IN SAFE-DOOR LOCKS.

The Schedule referred to in these Letters Patent and making part of the same.

TO ALL WHOM IT MAY CONCERN:

Be it known that I, JOHN GEORGE KRIECHBAUM, of Youngstown, in the county of Mahoning, and State of Ohio, have invented a new and improved Safe-Door Lock; and I do hereby declare that the following is a full, clear, and exact description thereof, which will enable those skilled in the art to make and use the same, reference being had to the accompanying drawings, forming part of this specification, in which—

Figure 1, Sheet I, represents a front view of the front plate and knob, showing the key-hole open.

Figure 2, Sheet I, is a vertical cross-section through the lock when the same is locked, the plane of section being taken through the shaft of the plate covering the key-hole, and through the knob.

Figure 3, Sheet I, is a vertical cross-section, taken through the key-hole and knob, showing the parts in position after the second move.

Figure 4, Sheet I, is a similar view, showing the parts in position after the third move.

Figure 5, Sheet I, is a sectional front view of the lower part of the safe.

Figure 6, Sheet I, is a plan or top view of the key-hole plate.

Figure 7, Sheet I, is a detail sectional view through the shank of the same, the plane of section being indicated by the line x, x , fig. 6.

Figure 8, Sheet II, is a front view of the first inner plate.

Figure 9, Sheet II, is a front view of the second inner plate.

Figure 10, Sheet III, is a front view of the third inner plate.

Figure 11, Sheet III, is a front view of the bolts on the fourth inner plate of the lock.

Similar letters of reference indicate corresponding parts.

This invention relates to a new safe-lock, which is so arranged that it cannot be opened, even with the correct key, unless the required movements are well known.

The bolts are arranged in pairs, moving in opposite directions, one bolt moving out while the other is thrown in by the key, so that there will always be one bolt out, which locks the door unless one bolt is, at the proper time and by the proper motion, thrown out of gear.

In the door no hole for the insertion of the key is to be seen when the door is locked, and the key-hole cannot be opened unless a certain plate is moved on the under side of the safe.

This lock is intended, when applied wholly as shown, to be fitted on safes which are set on wheels, so that the bottom of the safe is some distance above the floor of the apartment.

A represents the casing of the door at the under side of the same, (see figs. 2 and 5.) In the same is secured a vertical, tubular screw, a , the lower end of which is flush with the under side of the case. A small square or other-hole in the inside of the screw a allows the application of a small key, b , to the same, (see fig. 2,) whereby the screw a can be turned upward in the casing A.

The key-hole in a is, when the safe is locked, concealed by a sliding plate, c , arranged on the under side of the safe. This plate can be pressed up at its outer end, when its end will fit into a space, d , which is provided for its reception in the lower part of the casing A.

By throwing the outer end of the plate c up into the space d , and by then pushing it back toward and into the slot, the key-hole in a will be disclosed. A shoulder is formed on the plate c to allow its being pulled back again over the key-hole to conceal the same. In fig. 5 the key-hole a is represented as being covered by the plate c .

B is the front plate of the safe-door or of the lock. C is the back plate of the lock. Between the front and back plates are arranged, within the lock, four stationary vertical plates which divide the lock into five cells or departments. The plates are numbered respectively 1, 2, 3, and 4, and the compartments D, E, F, G, and H, as is clearly shown in fig. 2.

I is a bar, having a number of shoulders and grooves, to be hereinafter described. This bar is arranged horizontally, and passes through the plates B, 1, 2, 3, and 4, to the plate C, so that its inner end touches the same when locked, as in fig. 2.

In front, and on the outside of the plate B, the bar I is provided with a knob or handle, e, as shown in figs. 1 and 2. The key-hole in the front plate B is in a recessed portion of the said plate, the recess being, when the door is locked and the key removed, covered by a plate, J, as shown in fig. 2, said plate completely covering the key-hole and filling the aforesaid recess, and, being flush with the face of the door, the key-hole cannot be reached by burglars.

In the department E, between the plates 1 and 2, is arranged a vertical sliding bar, f, which has a horizontal arm on its upper end, as is shown by dotted lines in fig. 8. This horizontal arm fits into a recess, g, provided in the bar I between two shoulders, as shown in fig. 2, and thus the bar f locks the bar I, and the latter cannot be pulled out unless the horizontal arm of the bar f is raised out of the recess g. The bar f reaches down through the whole length of the safe-door, and its lower end rests upon the head of the screw a, as shown in fig. 2.

A recess is left above the head of the screw a, between the door and the casing A, as shown in fig. 2. When, therefore, the plate e has been moved aside, so as to clear the key-hole in a, and when, then, the key b has been inserted into the screw a, the latter can be screwed up, thereby raising the bar f, and raising the horizontal arm of the latter out of the recess g in the bar I.

h is another recess in the bar I, in front of the recess g, a shoulder, i, being between the recesses g and h, as is clearly shown in figs. 2, 3, and 4. A spring-plate, K, which is secured to the front of the plate 1, (see fig. 8,) is thrown into the recess h, when the bar I is moved in, as in fig. 2.

One side of the shoulder i is flattened or filed off, as seen in fig. 8, so as to be flush with the recesses g and h. When the bar I is released from the bar f, it must be turned, so that the flat side of the shoulder i comes in line with the edge of the plate K. Then the bar I can be pulled out a little.

The knob e should have a mark, which, when the knob is turned so that the mark is on the upper side, or in any other certain position, indicates the position of the bar I in which it can be pulled forward.

The plate J is secured upon an eccentric or other shank, k, (see figs. 6 and 7,) which fits through holes in the plates 1 and 2, as shown in fig. 2.

A notch or recess is cut into the shank k, as seen in figs. 2, 6, and 7.

When the plate J is closed over the key-hole, the spring-plate K is forced into the said notch, and thereby locks the plate J to the face of the door, (see also fig. 8.)

l is a spring, secured to the front of the plate 1, as seen in fig. 8, and forked at its free end, so as to fit around the shank k.

The spring l continually presses against a shoulder formed on the shank k, and therefore has a tendency to throw the plate J out, as soon as the spring-plate K releases the same.

When, therefore, the bar f has been moved up, by the action of the key b upon the screw a, the bar I will be released from its horizontal arm, and can be drawn out, when turned, so as to move clear of the plate K.

When the bar I is drawn out, so that the spring-plate K presses against the eccentric-shoulder, i, on the bar, and when the bar I is turned, the thicker part of the shoulder i will be brought against the plate K, and the same will be pushed aside, as shown by red lines in fig. 8. Thereby the shank k will be released from the plate K, and while thus momentarily released, it will be thrown forward by the action of the spring l.

The plate J will thus be thrown out of the recess in the plate B, and the key-hole in the plate B, which was covered by the plate J, will be disclosed by turning the plate J, as in fig. 1. On the end of the shank k is a head, provided with a screw-thread, as in fig. 2.

When the plate J is thrown out, it should be turned to the left, so as to screw the head into the plate 1, as the same would otherwise be in the compartment E, and would obstruct the turning of the main key in the said compartment.

The lower end of the bar f projects beyond the under side of the safe-door, as seen in figs. 5 and 8, and near to its extreme end it has a notch or recess, as shown.

When the door is all opened, the bar f may be pushed up by hand, and can be locked by a bolt, m, so as to be prevented from coming down again. The action of the key b and screw a can thus, for a time, be dispensed with. By turning the bolt m away from the bar f, the latter will, by its own weight, be thrown into the recess g as soon as the door is locked.

Upon the face of the plate 4 is secured a revolving disk, L, fig. 11, upon which a toothed wheel, n, is mounted.

M and N are the bolts, guided upon the plate 4, and fitted each to a toothed rack, as shown in fig. 11.

The rack o, which is connected to the upper bolt M, is pivoted to the same by a pin, p, so that the rack can be turned up, swinging around the pin p, as indicated by red lines in fig. 11. The rack q is fitted securely to the lower bolt N, and can only slide with the same.

Each bolt may be branched into two, or more or less, parts, which work into the casing of the door. They are guided between stops and pins in a suitable manner.

The racks o and q both mesh into the teeth of the wheel n, as is clearly shown in fig. 11. In the edge of the disk L are four, more or less, notches, fig. 11, for the reception of the bit of the key.

It will be seen that the bolts, when the disk L n is turned by the key, will move in opposite directions, as they mesh into opposite sides of the wheel n.

Between the plates L and 4 is interposed a sliding plate, r, which is slotted, so as to move on the pin around which the disks L n turn. A spiral spring throws it towards the key, and throws also a pin, s, into notches on the disk L.

When the key O is inserted, as shown in fig. 11, its bit will fit into one of the four, or more or less, large notches in the disk L, after it has thrown the tumbler r s out, and it can then turn the disk L n in either direction.

In fig. 11 it is represented as having turned the disk L as far as possible in the direction of the arrow 1, as in that position the lower bolt is pushed quite out, and the upper bolt is drawn quite in. The disk could no further be turned in that direction, owing to the stops against which the bolts strike.

In fig. 9, the key has been once turned, from the fig. 11 position, to the right. The upper bolt is pushed out one-fourth of its length; the lower bolt is drawn as much in.

In fig. 8, one more turn of the key has been made in that direction, both bolts projecting equally far from the edge of the door.

Thus it will be seen that when the door is locked, and the key inserted so as to strike against the plate 4, the door cannot be unlocked, as one of the bolts, at least, always projects into the casing of the door. Only when the upper rack o is turned up, so as to be out of gear with the wheel n, whereby the bolt M is disengaged from the key, can the lock be opened by drawing the bolt N in.

The bolt M, when to be thrown out of gear, must be drawn in, as in fig. 11, so as not to be in the way of opening the door. Then the rack o might be thrown up.

t is a horizontal pin, secured to the face of the plate o, and projecting through the plates 3 and 2, into the compartment E, as shown in figs. 2, 3, and 4.

In each plate 2 and 3 is a slot, to allow the pin t to move with the rack o and bolt M.

Upon the plate 3, is hinged a plate, P, which has a slot, u, fitting over the pin t, so that when the key is inserted to a certain mark, 2, so that the bit comes into the chamber F, it will be able to raise the plate P, and with it the rack o. A segmental slot, v, is for that purpose arranged in the plates 3 and 2.

But the upper part of the plate P strikes against the bar I, and therefore the rack o cannot be disengaged unless the bar I is drawn out so far that a narrow slot, w, of the plate P, will fit around a narrow portion of the bar I.

Upon the plate 2 is pivoted a plate, R, which has a curved neck, fitting over a recess, x, of the bar I.

The bar can therefore only be drawn out if the plate R is raised out of the recess, but this cannot be done unless the bolts are in one particular position, in which the pin t is brought over a small recess, y, of the plate R, (fig. 9,) whereby the plate R is allowed to be raised; otherwise it cannot be raised, as it would strike against the pin t.

The position required in the lock, when the same is arranged as in the drawing, is, that the bolt M should be pushed out one-fourth, and the bolt N three-fourths of its length.

When, now, the key is inserted to a certain mark, (1,) so that its bit comes into the compartment E, it will raise the plate R, and will raise it out of the recess x, as shown by red lines in fig. 9.

While the plate R is thus held raised by the bit of the key, the bar I can be drawn out, so that it will be in the position shown in fig. 4.

Then the narrow part, z, of the bar I, will be over the slot w of the plate P, (fig. 10,) so that the plate P might be raised to throw the rack o out of gear, if the pin t would be in line with the segmental slot v, but this is not the case as long as the bolt M is not quite drawn in, which it was not during the operation on the plate R.

Thus, after the plate R has been raised, and the bar I pulled out, the key must be brought against plate 4, and must be turned once around to the left, to draw the bolt M in; then it must be applied to the plate P, raise that, and with it the rack o.

The plate P has two notches, into one of which a catch, S, fits. When the plate is raised by the key, the catch S will hold it suspended, and thereby hold the bolt M out of gear as long as the key is not turned quite around in the compartment 3; therefore the key must be turned half-way round, and then back again. If turned quite round, it will come against a downward-inclining plane on the plate P, and will disengage the same from the catch S, and will make it drop down again.

I will now recapitulate the movements necessary for opening the lock.

The plate c must be drawn back, key b inserted, screw a screwed up. At the same time, the bar I must be drawn out.

Then the plate J jumps forward, and should be partly screwed to the left, to fasten it to plate 1.

Then the key should be inserted as far as possible, and should be turned to the left as often as possible, and then once to the right.

Then the key is inserted, (to the mark 1,) to raise the plate R. While raising the same, the bar I should be drawn out.

Then the key is again pushed to plate 4, and turned once to the left; then taken out, and inserted, (to mark 2,) to raise plate P. To do this, it is turned half round and back again; not wholly round.

Then the key is inserted again as far as possible, and turned to the right as often as possible, when the door will be open.

To lock, the proceeding is reversed.

The plate J may be formed on the key O, so as to be the knob or handle of the same. Then the shank k would be part of the stem of the key, with all its recesses, &c., and the key would be concealed in the lock, when the same is locked, no key-hole being required.

It will be seen that this lock allows a great many variations in its construction, and that it cannot be opened unless the exact formula for opening the same is known.

I claim as new, and desire to secure by Letters Patent—

1. The screw a, when operating as herein shown and described, in combination with the bar I, all made and operating substantially as herein shown and described.

2. The bar f, bar I, and plate K, when arranged as described, in combination with the spring l, shank k,

and plate J, (or stem *k* of key, and head J of the same,) all made and operating substantially as herein shown and described.

3. The bolts M and N, when the same are so arranged in one lock, that when one bolt is moved out, the other is drawn in, and *vice versa*, as set forth.

4. The rack o, when hinged to the bolt M, so that it can be turned up and thrown out of gear, as and for the purpose set forth.

5. The pin t, on the plate o, in combination with the slotted partitions 2 and 3, and hinged spring-plates P and R, all made and operating substantially as herein shown and described.

6. The plate P, when provided with a slot, w, and when combined with the pin t and bar I, all made and operating substantially as herein shown and described.

7. The plate P, when arranged in combination with the catch S, so that a full turn of the key will not keep it up, as set forth.

8. The plate R, when provided with a slot or recess, y, and when combined with the pin t and bar I, all made and operating substantially as herein shown and described.

9. The bar I, when provided with recesses g, h, and x, in combination with the plates K, f, R, and P, all made and operating substantially as herein shown and described.

JOHN GEORGE KRIECHBAUM.
